(57) **CLAIM**

The ornamental design for a buckle, as shown and described.

DESCRIPTION

FIG. 1 is a perspective view of a buckle showing my new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof;

FIG. 7 is a bottom plan view thereof;

FIG. 8 is a cross-sectional view thereof, taken along a line 8—8 of FIG. 3;

FIG. 9 is a perspective view thereof, wherein a male and female members of the buckle are separated;

FIG. 10 is a top plan view thereof; and,

FIG. 11 is a cross sectional view thereof, taken along a line 11—11 of FIG. 10.

The even broken line showings of a buckle of FIGS. 1-11 are for illustrative purpose only and form no part of the claimed design. The dot-dash broken lines of FIGS. 1-3, 6, 7, 9 and 10 define but are not included in, the boundaries of the claimed design.
